UNITED STATES PATENT OFFICE.

WILLIE D. WHITNEY, OF HOLLEY, NEW YORK.

WASHING-MACHINE.

1,108,047.

Specification of Letters Patent. Patented Aug. 18, 1914.

Application filed November 13, 1913. Serial No. 800,835.

To all whom it may concern:

Be it known that I, WILLIE D. WHITNEY, a citizen of the United States, residing at Holley, in the county of Orleans and State of New York, have invented a new and useful Washing-Machine, of which the following is a specification.

This invention relates to machines for washing clothes and the like, one of its objects being to provide a machine of this character utilizing a revoluble cylindrical fabric container disposed obliquely relative to its axis of rotation so that, during the rotation of the container, the fabrics therein will be caused to slide back and forth longitudinally of the container and will, at the same time, be subjected to a rolling action produced by the constant rotation of the container.

20 A further object is to provide means whereby the container may be adjusted angularly relative to its axis of rotation, thus to control the gravitation of the fabrics longitudinally of the container.

25 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

35 In the accompanying drawings the preferred form of the invention has been shown.

In said drawings:—Figure 1 is a central longitudinal section through the machine, a portion of the container being shown in elevation. Fig. 2 is a section on line A—B Fig. 1. Fig. 3 is a cross section through a portion of one of the heads. Fig. 4 is a perspective view of one of the bearing brackets used in connection with the machine. Fig. 45 5 is a perspective view of the other bearing bracket. Fig. 6 is a central longitudinal section through a portion of a modified form of machine, parts being broken away. Fig. 7 is a central vertical section through a portion of one of the heads of the modified form of container and showing the connection between said head and the jointed trunnion. Fig. 8 is a section on line C—D Fig. 7.

55 Referring to the figures by characters of reference 1 designates a casing having a substantially semi-cylindrical bottom 2, the said

casing being mounted on suitable supports 3 and being provided with any desired form of lid or cover 4. Journalled in one end of the casing is a shaft 5 which may be driven in any suitable manner, as by means of a crank 6 and secured to this shaft 5 is a sprocket 7. Secured to the inner side of that end of the casing 1 in which the shaft 5 is journalled is a bracket 8 having a bearing sleeve 9 at its lower end while arms 10 extend upwardly from this sleeve and are provided with slots 11 for the reception of attaching bolts 12. Thus it will be seen that the bracket can be adjusted upwardly or downwardly so as to bring the sleeve 9 to any desired distance from the shaft 5. Another bracket 13 is similarly connected to the inner side of the opposite end of the casing 1 but this bracket 13 is not provided with a sleeve 9 but, instead, is formed with a stirrup 14. Mounted for rotation in the casing is a cylindrical container 15 having its walls formed with perforations 16 and also provided with a door 17 which can be secured in closed position in any suitable manner. The cylinder has oblique but parallel heads 18 but it is to be understood that if preferred, the heads can be disposed at right angles to the longitudinal axis of the cylinder. Formed diametrically in the outer face of each head 18 is a guide groove 19 and slidably mounted in these grooves are blocks 20, each of which has a trunnion 21 outstanding therefrom. A set screw 22 or the like may be used for holding the block 20 against movement within the groove 19. Perforated partitions 23 may be arranged in the container 15 near the heads 18 and cleats 24 may be arranged longitudinally along the inner surface of the container and between the partitions. It will be understood that the trunnions 21 extend into the bracket, one of the trunnions being mounted in the sleeve 9 while the other trunnion is supported by the stirrup 14. The trunnion 21 extending into sleeve 9 is provided with a sprocket 25 and a chain 26 is mounted on this sprocket and on the sprocket 7 hereinbefore referred to.

In using the machine herein described, the lid or cover 4 is removed and the blocks 20 are adjusted longitudinally within the grooves 19 so as to bring them any desired distances from the centers of the heads 18, thus to position the container 15 any desired distance off center. The blocks are then se-

cured against further movement by means of the set screws 22 and the container 15 is rotated to bring the door 17 uppermost. The door is then opened and the fabrics to be cleaned are placed in the cylinder, after which the door is closed and the cleansing fluid is poured into the casing 1 so as to partly submerge the cylinder, as shown in Figs. 1 and 2. Cover 4 is then replaced and the container 15 rotated. Obviously, the fabrics contained therein will not only be rolled within the cylinder but will be caused to slide first toward one end and then toward the other end of the cylinder, the fabrics being thus subjected to a rubbing action within the cleansing fluid and which will result in the rapid cleansing of the fabrics. As the container 15 is cylindrical, the fabrics will slide gradually along the inner surface of the cylinder. By providing the cleats 24 the rolling action of the fabrics within the container is facilitated. Furthermore, by utilizing the perforated partitions 23, the water is permitted to flow freely through the fabrics while they are pressed against the partitions. It is to be understood that by having brackets adjustably mounted, as described, the container can be adjusted upwardly or downwardly within the casing 1, thus to loosen or tighten the chain 26.

As shown in Figs. 6, 7 and 8, the container 15' can have its trunnions 21' connected, by universal joints 27 to short shafts 28 and 29 respectively journaled in the end walls of the casing 30. Shaft 28 may be driven in any suitable manner, as by means of a gear 31, while shaft 29 merely rotates freely in its bearing. By providing a mounting such as herein described, it is possible to adjust one of the blocks 20' independently of the other so that the heads 18' instead of lying in vertical planes, will be disposed obliquely to the axis of rotation, it thus being possible to change the angle of the cylinder relative to the axis of rotation.

What is claimed is:—

1. A washing machine including a casing, a perforated cylindrical container mounted for rotation within the casing, the axis of rotation of the container being disposed at an acute angle to the longitudinal axis of

said container, perforated partitions within the container and constituting fabric abutments.

2. A washing machine including a casing, 55 a perforated cylindrical container mounted for rotation within the casing, the axis of rotation of the container being disposed at an acute angle to the longitudinal axis of said container, perforated partitions within 60 the container and constituting fabric abutments, and a cleat upon the inner surface of the container and between the partitions.

3. A washing machine including a casing, 65 a cylindrical container mounted for rotation therein, said container having heads, and a trunnion adjustable diametrically across each head.

4. A washing machine including a casing, 70 a cylindrical container mounted for rotation therein, said container having heads, a trunnion adjustable diametrically across each head, and shafts connected by universal joints to the respective trunnions, said shafts and trunnions coöperating to support the 75 container within the casing.

5. In a washing machine, the combination with a casing, of a container mounted for rotation therein, a trunnion connected to each end of the container and adjustable 80 diametrically thereacross, shafts journaled within the casing, and universal connections between the shafts and the respective trunnions.

6. A washing machine including a casing, 85 a container mounted for rotation therein, said container having heads provided with diametrical grooves, a block adjustably mounted in each groove, a trunnion extending from each block, means for securing the 90 blocks against movement within the grooves, shafts journaled in opposed walls of the casing, and universal connections between the shafts and the respective trunnions.

In testimony that I claim the foregoing 95 as my own, I have hereto affixed my signature in the presence of two witnesses.

WILLIE D. WHITNEY.
